Primary Examiner — David Muller(74) *Attorney, Agent, or Firm* — Fitch, Even, Tabin & Flannery, LLP(57) **CLAIM**

The ornamental design for a portion of a medical syringe with needle, as shown and described.

DESCRIPTION

FIG. 1 is a rear, top and right side perspective view of a portion of a medical syringe with needle, showing my new design;
 FIG. 2 is an enlarged fragmented view thereof, taken along the line 2-2 in FIG. 1;
 FIG. 3 is a front elevational view thereof; the opposite side being a mirror image thereof;
 FIG. 4 is a top plan view thereof;
 FIG. 5 is a bottom plan view thereof;
 FIG. 6 is a left side elevational view thereof;
 FIG. 7 is a right side elevational view thereof;
 FIG. 8 is an enlarged fragmented cross sectional view thereof, taken along the line 8-8 in FIG. 3;
 FIG. 9 is a cross sectional view thereof, taken along the line 9-9 in FIG. 7;
 FIG. 10 is a cross sectional view thereof, taken along the line 10-10 in FIG. 7;
 FIG. 11 is an enlarged fragmented view thereof, taken along the line 11-11 in FIG. 9; and,
 FIG. 12 is an enlarged fragmented view thereof, taken along the line 12-12 in FIG. 10.
 The dash and dotted lines immediately adjacent the shaded areas represent the bounds of the claimed design while all other broken lines are directed to environment only; the broken lines from no part of the claimed design.

1 Claim, 10 Drawing Sheets(56)
